UNITED STATES PATENT OFFICE.

S. PRENTISS NUTT, OF NATCHEZ, MISSISSIPPI.

TELEPHONE-TRANSMITTER.

SPECIFICATION forming part of Letters Patent No. 319,927, dated June 9, 1885.

Application filed February 12, 1885. (No model.)

To all whom it may concern:

Be it known that I, S. PRENTISS NUTT, a citizen of the United States, residing at Natchez, in the county of Adams and State of Mississippi, have invented certain new and useful Improvements in Telephone-Transmitters; and I do declare the following to be a full, clear, and exact description of the invention, such as will enable others skilled in the art to 10 which it appertains to make and use the same.

This invention has reference to transmitters for converting sound-waves or sonorous vibrations into corresponding waves, undulations, or vibrations of electricity by varying 15 the resistance of a circuit traversed by a galvanic current.

It relates more particularly to the current, changer, variable rheostat, or variable resistance, (sometimes called the "tension-regulator,") which is acted upon directly or indirectly by the sound-waves to produce the electrical undulations.

Heretofore this variable rheostat has been composed, commonly, of two or more solid conducting bodies or electrodes held in contact by yielding pressure. In some cases, however, a liquid of greater or less conductivity has been included in the circuit, so as to constitute a fluid electrode. In instruments having 30 this latter class of rheostats one or more solid electrodes have been moved up and down in the liquid by the action of the diaphragm upon which the sound-waves fall.

The present invention consists, first, in a new form of variable rheostat. A conducting-liquid constituting a fluid electrode is employed. It is placed in a chamber whose dimensions are variable under the action (direct or indirect) of the sound-waves. A tube 35 communicates with this chamber, so that the liquid, according to the pressure exerted on it in said chamber, will rise and fall in said tube.

An opposing electrode makes contact with the liquid in the tube, the rise and fall of which 45 liquid produce vibrations in the resistance of the rheostat. There are also suitable conductors for including the two electrodes in circuit.

In the instruments using a fluid electrode heretofore devised the movements of the solid

electrodes of course produce by displacement a slight rise and fall of the liquid in the receptacle; but this is essentially different from the rise and fall contemplated by the present improvement. The solid electrode has been so 55 small in comparison with the horizontal area of the liquid that the movement of the latter must be practically inappreciable. Moreover, there has been in such instruments nothing corresponding to the variable pressure-chamber and tube, the former filled, the latter partially filled with the conducting-liquid.

In order to diminish the mechanical resistance to the movements of the conducting-liquid as much as possible, the tube itself, or a 65 part of the tube, is made of conducting material, and constitutes the opposing electrode. This arrangement constitutes a second part of the invention.

Under the first part of the invention it is 70 not essential that the electrode should be or form part of the communicating tube. To the same end the pressure-chamber, instead of being made of variable dimensions by means of a piston or plunger, has one side or wall, or a 75 portion of one side or wall, formed of a thin or flexible plate or membrane, which plate or membrane is acted upon (directly or indirectly) by the sound-waves, and presses upon the contained liquid. Such a pressure-chamber, 80 not broadly, but in combination with the tube communicating therewith, the conducting liquid or fluid electrode filling the said chamber and partially filling the said tube, and the opposing electrode, which may be, and preferably is, the tube itself, or a part of said tube, constitutes the third part of the invention.

In order to increase the effect of the vibrations on the fluid electrode, the tube is made much smaller in cross-section than the area 90 of the movable part of the pressure-chamber, so that the movements of the fluid electrode in said tube are magnified. This arrangement or combination, including the opposing electrode, constitutes the fourth part of the invention. 95

A telephone-transmitter may be made in which the sole variation in resistance is due to the rise and fall of the conducting-liquid in the containing-tube. Such an instrument will be shown. The pressure-chamber and tube 100

with the contained liquid may, however, be used to vary the pressure between solid electrodes. In this case the column of liquid takes the place of the spring ordinarily used 5 to hold the pressure-electrodes in contact. As the column rises or falls, the pressure upon the electrodes correspondingly increases or diminishes. This use of a static column is not broadly new. It is, however, believed to be

10 new to make the bore of the tube much smaller in cross-section than the area of the movable part of the pressure-chamber, so as to increase the rise and fall in the tube and magnify the variations in pressure due to the rise and fall.

15 The invention fifthly consists in this combination or arrangement involving two pressure-electrodes, a variable pressure-chamber, a communicating tube whose bore is much smaller than the movable part of the pressure-chamber, and a liquid filling said chamber and partly filling said tube and serving to press the electrodes in contact.

According to the sixth part of the invention, an electrical connection with the electrodes is 25 established through a conducting-liquid in the pressure-chamber and tube.

In some instruments heretofore devised one of the electrodes has been partially depressed in mercury, the pressure of the displaced liquid holding it in contact with an opposing electrode, and the electrical connection has been made through the liquid. In these instruments, however, there was nothing corresponding to the variable pressure-chamber 35 and tube.

The invention seventhly consists in the combination of pressure-electrodes with a fluid electrode, its receptacle composed of pressure-chamber and tube, and the opposing electrode 40 in contact with said fluid electrode. One of the pressure-electrodes is or may be a part of the pressure-chamber, and the opposing electrode is or may be the communicating tube or a part thereof.

45 The invention also comprises certain particular constructions, combinations, and arrangements of parts, as hereinafter explained.

Referring to the accompanying drawings, which form a part of this specification, Figure 1 is a central vertical section of a telephone-transmitter constructed in accordance with the invention; Fig. 2, a plan of the same; Fig. 3, a partial view in horizontal section; and Figs. 4 and 5, central vertical sections of 55 other forms of telephone-transmitter, also constructed in accordance with the invention or with parts thereof.

In the instrument shown in Figs. 1, 2, the diaphragm A is horizontal. It is made of thin 60 metal, as usual, or preferably of carbon, and is included in the galvanic circuit whose resistance is to be varied. Of course, the diaphragm could be made of other suitable material, as well understood. The diaphragm is or 65 may be supported in any ordinary or suitable way. As shown, it rests at the edges upon an

annular shoulder of the frame B, and is clamped by the ring D, which is held down by the yoke C. One end of the yoke fits in a hole in lug 70 1 of the frame B, and the other is acted upon by the screw 2, tapped through a lug, 3, and bearing at the end against an incline, 4, on the yoke. The middle of the yoke bears upon the bridge E, attached to or in one piece with the ring D.

75 The devices which in connection with the diaphragm constitute the current-changer or variable rheostat of the instrument, are adjustably supported in the bridge E. They are as follows: A flexible plate or membrane, F, fastened over the enlarged end of the tube G, constitutes one side of a pressure-chamber, H, with which the tube G communicates. This chamber is filled and the tube G is partly filled with a conducting-liquid, I—mercury, for example. The plate F, as shown, not only constitutes the flexible wall of the pressure-chamber, but also acts as a contact or pressure electrode in connection with the diaphragm A. The plate is or may be made of thin platinum 90 secured by bending the edges over the annular rim 5 and cementing the same to said rim. The center of the plate is dished, so as to have a suitable bearing against the diaphragm. The tube G, and also the enlargement to form 95 the pressure-chamber, H is or may be of artificial carbon, such as used to make the buttons or pressure-electrodes of ordinary contact-telephones. The tube G, being made of conducting material, constitutes the opposing electrode 100 for operation in connection with the fluid electrode I. It is, however, properly the upper part, K, of the tube, including all above a point a little below the lowest point to which the mercury descends. The rest of the tube 105 need not be conductive, although when the tube is of a material of low conductivity—such as carbon—it may be.

110 The tube G fits within the sleeve L, of non-conducting material—hard rubber, for example—and is secured in the bridge E by the set-screw 6, tapped through the metal of the bridge, and passing through a hole in the sleeve L and bearing at the end against the outside of the tube G. This set-screw is made of or tipped 115 with non-conducting material, so as to insulate the tube G from the bridge.

120 The electrode K, making part of the tube G, is provided with a band, 7, whose ends are drawn together by the screw 8. By means of this band the electrode is connected with the circuit-wire. The bore of the tube is much smaller than the area of the flexible wall and pressure-electrode F. It is or may be closed at the upper end by a plug, 9.

125 The operation will be readily understood. The tube G is properly adjusted in the bridge E, so that the electrode or flexible plate F bears upon the diaphragm A, which is also an electrode, with the proper degree of pressure, ascertained by the usual tests. The circuit is through the diaphragm A, the plate or 130

solid pressure-electrode F, the mercury or fluid electrode I, and the opposing electrode K. When the tube G is wholly of conducting material, some of the current, of course, traverses the whole length of the same. Upon talking into the mouth-piece M the sound-waves, acting directly upon the diaphragm A and indirectly upon the flexible wall F of the pressure-chamber H and vary its dimensions, causing the liquid I or fluid electrode to rise and fall in the tube G. In consequence of the relative dimensions of the pressure-chamber and the tube, the liquid has a comparatively large movement in the tube and in contact with the opposing electrode K, formed by the upper part of said tube. When the liquid rises, the resistance of the instrument is diminished; when it falls, it is increased. The resistance is diminished by the rise of the liquid, not only in consequence of the increased area of contact between the fluid electrode I and the opposing electrode K and the diminished distance between the top of the mercury-column and the circuit-wire, but also because the pressure of the electrode F against the diaphragm is increased as the mercury-column is higher. There is also a variation of resistance due to the variations in pressure between the diaphragm A and the electrode F, due to the inertia of the liquid, the frictional resistance which it encounters, and the lack of perfect flexibility in plate F. Very good articulation has been obtained with an instrument constructed as described.

Instead of using the precise arrangement described, a button, F', Fig. 4, of carbon or other suitable material, may be used as the pressure-electrode to rest upon the diaphragm A. It is connected by a small cylinder, H', of thin sheet-rubber, with the tube G, which is secured in the bridge E, as above described. The elasticity of rubber H' allows the button F' to rise and fall with the diaphragm, so as to press more or less on the mercury I and cause it to rise and fall in the tube G. The other parts of the instrument are the same as in Figs. 1, 2, and 3, except that rubber rings 10 are placed on either side of the diaphragm A at the edges. These rings could of course be used in other instruments, suitable means being used in all cases to connect the diaphragm in circuit. The rubber cylinder H' can be fastened to the button F' and tube G by wrapping with silk thread.

It is not essential to communicate the movements to the fluid electrode I, by means of a movable pressure-electrode forming part of the wall of the pressure-chamber; nor is it necessary to use a solid pressure-electrode at all. An instrument of this kind is shown in Fig. 5. A thin sheet of rubber, F'', is stretched across one side of the pressure-chamber H, formed by the enlargement of the tube G. A metal pin, N, attached to the center of the diaphragm, passes through the rubber F'' and makes contact with the liquid I. A

small disk, 11, fixed on the pin N, presses against the rubber membrane F''. In this instrument there is no variation in resistance by the variable pressure between solid electrodes. The diaphragm is placed vertically, the tube G being bent so as to make the outer part vertical. The rest of the instrument is the same as in Figs. 1, 2, and 3.

Various other modifications could be made without departing from the spirit of the invention, and parts of the invention could be used separately.

I claim the new improvements herein described, all and several, to wit:

1. The current-changer or variable rheostat of a telephone-transmitter, comprising a variable pressure-chamber and a conducting liquid or fluid electrode, in combination with an opposing electrode and a tube communicating with said chamber, the sonorous vibrations acting through said pressure-chamber to produce a rise and fall of the liquid in said tube in contact with the opposing electrode, substantially as described.

2. The combination of a variable pressure-chamber, a conducting liquid or fluid electrode, a tube communicating with said chamber, and an opposing electrode formed by or forming a part of said tube, substantially as described.

3. The current-changer or variable resistance of a telephone-transmitter, comprising a conducting liquid or fluid electrode, a pressure-chamber having a flexible wall, a communicating tube into which the said liquid rises, and an opposing electrode in contact with the liquid in the tube, substantially as described.

4. The current-changer or variable rheostat of a telephone-transmitter, comprising a conducting liquid or fluid electrode, an opposing electrode in contact with the former, and means for increasing the effect of the sonorous vibrations in varying the resistance, said means consisting of a pressure-chamber having a relatively large movable part to be actuated by the vibrations and a contracted tube of much smaller bore communicating with said chamber, substantially as described.

5. In a telephone-transmitter, the combination, with two solid or pressure electrodes, of a variable pressure-chamber having a relatively large movable part, a tube of much smaller bore communicating with said chamber, and a liquid filling said chamber and partly filling said tube for pressing the electrodes into contact, the said liquid, under the action of the sound-waves, rising and falling in said tube, and thus varying the pressure upon said electrodes, and the said variations being magnified in consequence of the relatively small bore of the tube, substantially as described.

6. The combination, with two pressure-electrodes, of a variable pressure-chamber, a communicating tube, a column of conducting-liquid,

uid filling said chamber and partly filling said tube for pressing said electrodes into contact, and conductors for establishing an electrical connection with the electrodes through the 5 said liquid, substantially as described.

7. The combination, with the two pressure-electrodes, of the pressure-chamber, the communicating tube, the conducting-liquid constituting a fluid electrode in said chamber and 10 tube, and the opposing electrode in contact with the liquid in the tube, substantially as described.

8. A telephone-transmitter comprising the following elements in combination, namely: 15 a diaphragm, a pressure-chamber whose dimensions are varied by the vibrations impressed upon the diaphragm, a tube communicating with said chamber, a conducting liquid or fluid electrode rising in said tube, and 20 an opposing electrode in contact with said liquid in said tube, substantially as described.

9. The current-changer or variable rheostat of a telephone-transmitter, composed of a carbon tube and a column of mercury which is 25 caused to move in said tube in accordance with the vibrations to be transmitted, substantially as described.

10. The variable pressure-chamber provided with a flexible wall, and composed, mainly, of 30 carbon, in combination with the carbon tube communicating therewith, and the fluid electrode of mercury, substantially as described.

11. The current-changer or variable rheostat of a telephone-transmitter, comprising a column of conducting-liquid, which constitutes a 35 fluid electrode, and which is made to rise and fall under the action of the sound-waves, in combination with a stationary opposing electrode.

12. The combination, with a stationary pressure-chamber and tube, said pressure-chamber having a flexible wall which is acted upon by the sound-waves, of a conducting liquid or fluid electrode in said chamber and tube, and a stationary opposing electrode, substantially 45 as described.

13. The combination of the diaphragm held in the stationary frame with the variable pressure-chamber and tube adjustably supported in the stationary frame, the conducting liquid or 50 fluid electrode in said chamber and tube, and the opposing electrode in contact with the liquid in the tube, substantially as described.

14. The combination, with the column of conducting-liquid which constitutes the fluid 55 electrode and is caused to rise and fall under the influence of the sound-waves, of an opposing electrode in contact with said column, and a conductor attached to said opposing electrode above the top of said column, substantially as described.

15. The combination of the variable pressure-chamber, the communicating tube, the fluid electrode, the opposing electrode at the upper end of said tube, and conductors for 65 putting one terminal of the circuit in electrical connection with the liquid in the pressure-chamber and the other terminal in connection with the top of said opposing electrode, substantially as described. 70

In testimony whereof I affix my signature in presence of two witnesses.

S. PRENTISS NUTT.
